ABSTRACT OF THE DISCLOSURE

Multihead fully fashioned knitting machines have a single control division and a plurality of knitting divisions. Racking of the fashioning mechanisms is effected by racking mechanisms and associated bluff plate mechanisms. The racking mechanisms and the bluff plate mechanisms are operable through linkage systems which are mechanically interconnected in such manner that they operate, during at least part of their operational movement, as one. A single power unit is provided to actuate both said racking mechanisms and said bluff plate mechanisms.

This invention relates to multihead fully fashioned knitting machines of single or twin bed construction having individually operated needles, and is concerned with knitting width control apparatus for such machines.

In particular, the invention is applied to such knitting machines and of the kind, hereinafter referred to as of the kind described, comprising a plurality of knitting divisions, each consisting of a single needle bed, or two co-operating needle beds, and L.H. and R.H. fashioning mechanisms associated with each needle bed, a control division, which includes a L.H. fashioning screw and a R.H. fashioning screw in respect of the or each series of needle beds, the fashioning screws each being provided with a nut housing movable lengthwise thereof, said nut housings being coupled to the respective L.H. and R.H. fashioning mechanisms of the or each series of needle beds, a racking mechanism associated with each of the fashioning screws, and a bluff plate mechanism associated with each racking mechanism. It will thus be appreciated that, in the case of a twin bed machine, the control division houses two pairs of oppositely handed fashioning screws, one pair controlling the lengthwise movement of the fashioning mechanisms of one series of needle beds and the other pair controlling the lengthwise movement of the fashioning mechanism of the other series of needle beds. In the case of a single bed machine it will be obvious that only one pair of fashioning screws are required.

According to the present invention, in a fully fashioned multihead knitting machine of the kind described, the racking mechanisms and their associated bluff plate mechanisms are mechanically interconnected and are operated by actuating means which are common to both mechanisms.

Preferably, the actuating means comprise a fluid operated ram.

According to the invention furthermore, each racking mechanism comprises two rackwheels provided with oppositely directed teeth for engagement by co-acting racking pawls, and each bluff plate mechanism comprises a bluff associated with each rackwheel, means being provided for controlling the position of one of the bluff plates so that the racking mechanism is caused to move the nut housing of one fashioning screw either one needle width or two needles width, and for controlling the position of the other bluff plate so that the pawl associated

2

therewith remains inoperative during the racking operation.

According to a further feature of the invention the means for controlling the positions of the bluff plates comprise, in association with each bluff plate, solenoid actuated stop means which are operable selectively to achieve the desired result.

The invention is illustrated by way of example in the accompanying drawings in which,

FIGURE 1 is an elevation of part of a multihead knitting machine incorporating the invention which shows the L.H. fashioning screw and part of the R.H. fashioning screw of the control division and, schematically, one of the knitting divisions, it being understood that for clarity certain parts both of the control division and the knitting division have been omitted,

FIGURE 2 is a section, with certain parts omitted for clarity, on the line 2—2 of FIGURE 1,

FIGURE 3 is a detail, on an enlarged scale, of the right hand part of FIGURE 2,

FIGURE 4 is a schematic elevation showing the index boxes associated with the L.H. and R.H. fashioning screws in the control division,

FIGURE 5 is a perspective view, partly broken away, of one of the index boxes shown in FIGURE 4, and,

FIGURE 6 is an electrical diagram.

Referring to the drawings, there is provided a flat bed knitting machine comprising a plurality of knitting divisions one of which is shown at 10 and a control division 11, each knitting division 10 including front and rear needle beds, one of which is shown at 12, each of which needle beds has operatively associated therewith L.H. and R.H. fashioning mechanisms 13 and L.H. and R.H. knitting width control means 14.

The control division 11 is provided, in respect of each series of front or rear needle beds 12, with a pair of co-axial oppositely handed fashioning screws, the L.H. screw 15 having mounted thereon for lengthwise movement thereof a nut housing 16 which is coupled, through a control rod 17 to the L.H. fashioning mechanism 13 of each knitting division 10 of the series and, via a control rod 18, to the L.H. knitting width control means 14 of each knitting division 10 of the series. The R.H. fashioning screw 19 similarly has mounted thereon a nut housing (not shown) which is coupled, through a control rod 20, to the R.H. fashioning mechanism 13 and, via a control rod 21 to the R.H. knitting width control means 14.

In this latter respect, it will be appreciated that, since the R.H. fashioning screw 19 and its associated parts are a mirror image of those shown with respect to the fashioning screw 15 the drawing of FIGURE 1 is restricted to showing only the L.H. fashioning screw 15 and its associated parts in full. Similarly, since the machine being described has front and rear needle beds, it will be understood that the fashioning screws 15 and 19, and their associated parts, are repeated in exactly the same manner on the opposite side of the machine, the R.H. fashioning screw on the opposite side being indicated at 19' in FIGURE 2.

Each fashioning screw 15 or 19 has fixedly mounted on an extension 30 of one end thereof a racking mechanism which comprises two rackwheels 23 and 24 provided respectively with oppositely directed peripheral teeth, which are arranged to be engaged by oppositely acting racking pawls 25, 26 which are biased into engagement with said teeth and are arranged to cause turning movement of the fashioning screw 15 or 19 and thus lengthwise movement of the nut housing 16 mounted thereon. Thus, it will be understood that turning movement of rackwheel 23 effects racking in of the nut housing 16 to cause narrowing of the garment piece and turn-

ing movement of rackwheel 24 effects racking out of the nut housing 16 to cause widening of the garment piece.

In order to control the action of the racking pawls 25 or 26 to cause widening or narrowing of the garment piece by say one or two needle widths, each rackwheel and pawl has associated therewith a bluff plate 28 having a cutout portion 29 the plate being movable to expose the teeth of the racking pawl to permit of the latter to turn the rackwheel by one tooth, or by two teeth, or to cause the pawl to remain inoperative. In this respect, it will be obvious that when operating the rackwheel 24 to effect widening of the garment piece, the other rackwheel 23 remains inoperative due to the fact that the bluff plate 28 holds the racking pawl out of engagement with the teeth thereof.

Each of the pawls 25, 26 is mounted on one end of a stub axle 31 which is supported in a bearing boss 32 arranged on an annular support 33, the latter being mounted, for angular turning movement, relative to its coacting rackwheel, on the extension 30. The other ends of the stub axles 31 supporting the pawls 26 each have attached thereto a connecting link 34 which links are hingedly secured to one arm 35 of a bellcrank lever 36 which is keyed to a shaft 37 mounted in bearing brackets 38 secured to the frame 39 of the machine. The other ends of the stub axles 31 supporting the pawls 25, in a similar manner to that of the pawls 26, have attached thereto connecting links 40 which are hingedly secured to link arms 41 also keyed to the shaft 37. A similar arrangement is provided for the other needle bed of the machine and, as shown in FIGURE 2, the relevant parts in this case are indicated by the suffix *a*. The other arms 42 and 42a of the bellcrank levers 36 and 36a are interconnected by a connecting link 43 so that the two mechanisms can be operated by a single power unit generally indicated at 44.

The power unit 44, as shown in FIGURE 2, comprises a double acting hydraulic ram 45 the cylinder of which is hingedly secured to the frame 39 and the piston rod 46 of which is hingedly connected to one end of a double-ended lever 47 pivotally attached to the frame 39. The other end of the lever 47 is connected via an actuating rod 48 to the arm 35a of the bellcrank lever 36a. Thus, it will be understood that all the pawls 25, 26, 25a, 26a of both the L.H. and R.H. fashioning screws 15 and 19 of both needle beds 12 are operated by a single hydraulic ram.

The bluff plates 28 associated with each rackwheel 25, 26 are each coupled by means of a link rod 49 to one arm 50 of a three armed lever 51 which is turnably mounted on the shaft 37 so that the bluff plates can be operated independently of the racking pawls and moved relative thereto. A second arm 52 of the lever 51 is connected, via a connecting link 53, to a corresponding lever and link rod associated with each bluff plate 28a arranged for co-operation with the rackwheels of the opposite needle bed.

The bluff plate linkages 49, 51 are biased, by a tension spring 54 which extends between the lever 51 and a bracket 55 fixed to the frame 39, in a direction where the bluff plates 28 are urged into a fully retracted position and in a direction which is away from the fully racked position of the racking pawls 25, 26.

In operation, in order to effect racking movement, the hydraulic ram 44 is actuated to carry out a single stroke, i.e., it is moved from the extended position shown in FIGURE 2 to the retracted position, which is effective to cause retraction of all the racking pawls 25, 26. During this movement, selected bluff plate linkages 49, 51 are also allowed to move, under the action of their tension springs 54, in a direction towards the fully retracted position of the bluff plates 28, the reason for this being that the bluff plate linkages 49, 51 are normally prevented, when the racking pawl linkages 36 and 34 or 40 are in their fully racked position, from moving since they

are normally in mechanical engagement with stop rods 56 arranged on the lever 36 of their coacting racking pawl linkages. The extent of movement of the bluff plate linkages 49, 51 is controlled by stops, hereinafter described, to give the desired result. Thus, if it is desired to rack one needle width in one direction, the bluff plate 28 of one rackwheel of each fashioning screw is stopped at a position where one tooth is exposed and the bluff plate 28 of the other rackwheel of each fashioning screw is stopped at a position where the racking pawls are maintained out of engagement with the teeth of their coacting rackwheels.

On the return stroke of the ram 44, i.e., the racking stroke where the ram is extended, the said one rackwheel 5 of each fashioning screw is turned taking with it the said 15 other rackwheel which is turning in a direction which is against the normal action of movement effected by its coacting racking pawl. Immediately prior to the end of the racking stroke, the pawl of the said other rackwheel 20 of each fashioning screw enters into engagement with its coacting teeth to provide a stop which prevents any tendency on the part of the fashioning screw to overrun its intended extent of movement.

The means for stopping the movement of the bluff 25 plates in one of a number of predetermined positions comprise, in respect of each bluff plate linkage 49, 51, stop levers 57, 58 which are pivotally mounted at 58a on the bracket 55 and which are actuated individually by means of solenoids 59, 60 the operation of which is 30 controlled, for example, by a punched tape or other control means.

Thus, it will be appreciated that, in operation, the racking linkages 36 and 34 or 40 are operatively connected to the bluff plate linkages 49, 51 by virtue of their being 35 biased into engagement and that racking movements in both directions are carried out by means of the single ram 44. The advantage of the operative connection between the racking linkages and the bluff plate linkages is that it dispenses with the use of relatively large solenoids 40 for actuating the bluff plates as distinct from the solenoids actuating the stop levers, the bluff plate solenoids tending to burn out due to over heating, and utilises only very light solenoids as a means for selecting the extent of movement of the bluff plates and not for actually moving them.

As can be seen from FIGURE 3, the stop levers 57, 58 are biased by spring means 60 into a position where they are arranged to engage a stop pin 61 mounted on their co-operating lever 51 to limit the extent of angular movement of the latter. The arrangement is such that each stop lever can be moved by its coacting solenoid into one of two positions. In the operative position the lever 57 shown in solid lines is such as to prevent any movement, which would result from movement of the racking lever 36, of the lever 51 so that the coacting bluff plate 50 would be held in the position "0" and racking of that particular rackwheel would not take place. In the inoperative position of the lever 57 shown in broken lines, the latter is bypassed and control is taken up by the lever 58. In the operative position the lever 58 shown in solid lines is effective to stop the movement of the lever 51 at the position "N1" where the bluff plate 28 is positioned to expose one tooth of its co-operating rackwheel so that the racking pawl is operable to effect racking by one needle width. In the inoperative position of the lever 58 shown in chain dot lines, the latter is bypassed and control is taken up by a third arm 62 of the lever 51 which stops movement of the latter by entering into engagement with the frame 39 in position "N2." In this position it will be appreciated that the bluff plate is moved so that racking by two needle widths is effected. It will therefore be understood that each bluff plate linkage 49, 51 is capable of taking up three different positions according to whether it is desired to rack by one or two needle widths or, where racking is to take place in the opposite direction, not to rack at all. Thus, by suitable selection of the positions of

the levers 57, 58, racking in and racking out can be effected to suit requirements.

In addition to the normal racking operation described above, the present invention also includes in combination therewith means for resetting the nut housings on each fashioning screw on completion of a garment piece. These means include two switch boxes 63, 64 controlling respectively the front L.H. screw 15 and the rear L.H. screw (not shown), and the front and rear R.H. screws 19, 19'. The switch boxes 63, 64 are set by the operator to give any desired knitting width, which width is normally the starting width of a garment piece and the boxes are then locked in position on a supporting indicator bar 65 by means of a locking lever 66.

The switch boxes each include two switches and a cam 67 which can be turned to break the circuit of both switches, or to complete the circuit of one or other of the switches. The box 63 has switches S.91 and S.92 and box 64 has switches S.93 and S.94, contact being made therewith by two pivoted arms 68, 69 which are biased into engagement with the cam 67 by means of a spring 70. The spindle 71 on which the cam 67 is mounted is provided with a downwardly depending switch arm 72, the end of which is bifurcated to engage a projection 73 provided on an indicator rod 74 fixed to and movable with the nut housing 16 of its coating fashioning screw.

The purpose of the switch boxes 63, 64 is to determine the direction of movement which has to take place to reset the nut housings in their starting positions. Thus, at the start of a garment piece, the switch boxes 63, 64 and the nut housings are in the same relative positions where the switch arm 72 is in a vertical position and the circuit to both switches is broken. During operation to knit a garment piece, the nut housing 16 will move relative to the switch boxes 63, 64 and, in doing so, will trip the switch arm 72 to complete the circuit to one of the switches. When, on completion of the garment piece, it is required to reset the positions of the nut housings, the actuated switch will complete a control circuit which will dictate the direction of movement to bring the nut housings back into alignment with the switch boxes. It will be understood that any relative movement between the switch boxes and the nut housings where the two pass each other, whether it be in normal operation of the machine, or movement effected by the operator, is such as to operate the switch boxes.

During resetting, the appropriate racking mechanism is operated to rack continuously until the positions of the nut housings correspond to the positions of the switch boxes when the operation of the racking mechanism will be stopped. In this respect, racking on one or both screws will continue until both nut housings are in their correct positions. Thus, the extent of racking movement of both nut housings need not be symmetrical.

It will be understood that resetting means are incorporated in the machine using the normal racking mechanism and without the addition of further mechanisms.

As mentioned above, the operation of the racking mechanisms may be controlled by a punched tape. In the case of the resetting mechanism however, it is preferred to provide a separate control circuit, which may be actuated manually or by the tape, the operation being such that, on completion of a resetting operation, control of the machine returns to the tape.

As regards the racking operation it will be seen that, although the bluff plates are operated individually insofar as their extent of movement is controlled by their individual stop levers, the racking pawls of all the rackwheels operate, under the action of the hydraulic ram, collectively irrespective of whether a racking-in or a racking-out operation is to be performed. Furthermore, where the shape of the garment piece is such that the action of the racking mechanisms is repetitive, the stop means associated with the relevant bluff plates can be permanently

selected for a predetermined number of courses or they can be cancelled out and reset for each operation.

Referring now particularly to FIGURE 6 which shows the electrical circuit with reference to a machine capable of widening by one needle width (solenoids 59'), narrowing by one needle width (solenoids 59) or narrowing by two needles width (solenoids 60), it will be understood that, in order to rack the fashioning screws, the screw racking ram 44 is caused to retract and then allowed to be returned to its extended position. The direction of the rack and the distance racked is determined by the selection made from a control unit, which may be a punched tape and which controls the operation of the whole machine. Thus, the appropriate rack direction solenoids 59, 59' or 60 are energised from the control unit via relays R.84 and R.85. Relay R.93 is impaled by R.86 (which is a signal from the control unit) and held energised by switch S.96 and "hold on" contact R.93/1. The screw racking valve solenoid 75 (see also FIGURE 2) is energised via R.93/2 which causes the racking ram 44 to retract. When the racking ram 44 is fully retracted, switch S.96 (which is located on the actuating rod 48) is operated and relay R.93 is de-energised allowing the racking ram to return to its extended position. Racking of the fashioning screws is effected on completion of this sequence.

In order, on completion of a garment piece, quickly to return the nut housings to their indexed position in the appropriate direction, the racking mechanism is continually racked. To effect this, the appropriate direction solenoid 59, 59' or 60 also need to be energised, the direction being determined by switches S.91(a), S.92(a), S.93(a) and S.94(a) in the indexing boxes 63, 64 which are biased by the direction which the screws have been previously racked. Thus, relay R.76 is energised either by an impulse signal from the control unit R.75 or by a manually operated push button S.90. R.76 is held energised by R.76/1 and any one or more of the switches S.91(b), S.92(b), S.93(b) and S.94(b). The other pole of these switches S.91(a), S.92(a), S.93(a) and S.94(a) is used to give the direction of the screw racking. When relay R.76 is energised R.76/2, R.76/3, R.76/4 and R.76/5 enable the switches in the indexing boxes 63, 64 to become effective.

Energising relay R.76 also closes the contacts R.76/6 which allows relay R.93 to become energised and in turn energises the screw racking valve solenoid 75 via contacts R.93/2, the racking ram 44 being retracted. When the racking ram has left its extended position switch S.82 opens but the screw racking valve solenoid 75 remains energised due to switch S.96 and contact R.93/1. When the screw racking ram has reached its fully retracted position switch S.96 opens which de-energises relay R.93 and therefore the screw racking valve solenoid 75, which allows the screw racking ram 44 to return to its extended position, but contrary to the case described above, as soon as it reaches its extended position switch S.82 closes and re-energises relay R.93 and the screw racking ram 44 is again retracted. In this way the screw racking ram 44 is self oscillating until both the indexing boxes 63, 64 have returned to their neutral positions.

When both the indexing boxes 63, 64 have returned to their neutral positions relay R.76 is de-energised and the screw direction solenoid circuits 59, 59' or 60 are changed over to the control unit.

By using hydraulic power to operate the fashioning screws, it will be obvious that the invention provides the advantage that these can be operated independently of the rest of the machine and can for example be operated when the machine is stationary.

Furthermore, by connecting the racking means and the bluff plates mechanically, it makes it impossible for the front screws and the rear screws to be out of phase with one another.

With further reference to the operation of the stop

levers 57, 58 it will be appreciated that, in order to enable the bluff plate lever 51 to move into position "N2," it is necessary to move both stop levers 57, 58 into an inoperative position where they are bypassed by the lever 51. This can of course be effected by arranging the electrical circuit so that both solenoids 59, 60 are operated simultaneously but it is preferred to provide a mechanical connection between the levers 57 and 58 to cover this eventuality. Thus, each lever 58 is provided, at a position between the pivot 59 and a point corresponding to the right hand end of the lever 57, with a hook-shaped member arranged to hook over the lever 57. Thus, movement of the lever 58 into an inoperative position also causes similar movement of the lever 57 so that both levers do not engage the stop pin 61 on the lever 51.

Although the invention has been specifically described with reference to a twin bed machine, it will be obvious that, by dispensing with the linkages on one side of the machine, and with the connecting links 43 and 53, it can be applied to a single bed machine.

What I claim is:

1. A multihead fully fashioned knitting machine comprising a plurality of knitting divisions each of said knitting divisions consisting of at least one needle bed and L.H. and R.H. fashioning mechanisms operatively associated with said needle bed, a control division which includes a L.H. fashioning screw and a R.H. fashioning screw operatively associated with said needle bed, a nut housing mounted for lengthwise movement on each of said fashioning screws, said nut housings being coupled respectively to said L.H. and said R.H. fashioning mechanisms, a racking mechanism associated with each of said fashioning screws, and a bluff plate mechanism associated with each of said racking mechanisms, wherein said racking mechanisms and said bluff plate mechanisms are mechanically interconnected during at least part of the operational movement of the racking mechanisms, and a single power unit is provided to actuate both said racking mechanisms and said bluff plate mechanisms.

2. A multihead fully fashioned knitting machine comprising a plurality of knitting divisions each of said knitting divisions consisting of at least one needle bed and L.H. and R.H. fashioning mechanisms operatively associated with said needle bed, a control division which includes a L.H. fashioning screw and a R.H. fashioning screw operatively associated with said needle bed, a nut housing mounted for lengthwise movement on each of said fashioning screws, said nut housings being coupled respectively to said L.H. and said R.H. fashioning mechanisms, a racking mechanism associated with each of said fashioning screws, and a bluff plate mechanism associated with each of said racking mechanisms, wherein spring means extend between a fixed part of the machine and said bluff plate mechanisms to bias said racking mechanisms and said bluff plate mechanisms into engagement with one another so that they operate as one during at least a part of the operational movement of said racking mechanisms, and a single power unit is provided to actuate both said racking mechanisms and said bluff plate mechanisms.

3. A multihead fully fashioned knitting machine comprising a plurality of knitting divisions each of said knitting divisions consisting of at least one needle bed and L.H. and R.H. fashioning mechanisms operatively associated with said needle bed, a control division which includes an L.H. fashioning screw and a R.H. fashioning screw operatively associated with said needle bed, a nut housing mounted for lengthwise movement on each of said fashioning screws, said nut housings being coupled respectively to said L.H. and R.H. fashioning mechanisms, a racking mechanism associated with each of said fashioning screws, said racking mechanisms each comprising two rackwheels having oppositely directed teeth, a racking pawl operatively associated with each of said rackwheels, and means for moving said racking pawls rel-

ative to said rackwheels, and a bluff plate mechanism associated with each of said racking mechanisms, said bluff plate mechanisms each comprising a bluff plate operatively associated with each of said rackwheels and means for moving said bluff plates relative to said rackwheels, wherein said racking mechanisms and said bluff plate mechanisms are mechanically interconnected during at least a part of the operational movement of said racking mechanisms, and a single power unit is provided to actuate both said racking mechanisms and said bluff plate mechanisms.

4. A knitting machine as claimed in claim 3, wherein said racking pawls of each of said mechanisms are controlled collectively and said bluff plates of each of said mechanisms are controlled individually, a linkage system connecting each of said racking pawls to said power unit, a linkage system operatively associated with each of said bluff plates, spring means for biasing said bluff plate linkage systems into engagement with stop rods associated with said racking pawl linkage systems, and stop arms for controlling the extent of movement of said bluff plate linkage systems and thus also of said bluff plates.

5. A multihead fully fashioned knitting machine comprising a plurality of knitting divisions each of said knitting divisions consisting of a front needle bed and a rear needle bed and L.H. and R.H. fashioning mechanisms operatively associated with each of said needle beds, a control division which includes an L.H. fashioning screw and a R.H. fashioning screw operatively associated with each of said needle beds, a nut housing mounted for lengthwise movement on each of said fashioning screws, said nut housings being coupled respectively to said L.H. and said R.H. fashioning mechanisms, a racking mechanism associated with each of said fashioning screws, said racking mechanisms each comprising two rackwheels having oppositely directed teeth, a racking pawl operatively associated with each of said rackwheels, and a linkage system operatively associated with each of said racking pawls, and a bluff plate mechanism associated with each of said racking mechanisms, said bluff plate mechanisms each comprising a bluff plate operatively associated with each of said rackwheels and a linkage system operatively associated with each of said bluff plates, spring means biasing said bluff plate linkage systems into engagement with said racking pawl linkage systems so that both of said linkage systems operate as one during at least a part of their operative movement, connecting links extending respectively between said racking pawl linkage systems and said bluff plate linkage systems associated with said front needle beds and said racking pawl linkage systems and said bluff plate linkage systems of said rear needle beds, and a single power unit coupled to said racking pawl linkage system to actuate both said racking pawls and said bluff plates.

6. A multihead fully fashioned knitting machine comprising a plurality of knitting divisions each of said knitting divisions consisting of the least one needle bed and L.H. and R.H. fashioning mechanisms operatively associated with said needle bed, a control division which includes an L.H. fashioning screw and a R.H. fashioning screw operatively associated with said needle bed, a nut housing mounted for lengthwise movement on each of said fashioning screws, said nut housings being coupled respectively to said L.H. and said R.H. fashioning mechanisms, a racking mechanism associated with each of said fashioning screws, a bluff plate mechanism associated with each of said racking mechanisms, spring means interconnecting said racking mechanisms and said bluff plate mechanisms during at least a part of the operational movement thereof, a single power unit to actuate both said racking mechanisms and said bluff plate mechanisms, and adjustably mounted switch boxes operatively associated with each of said nut housings of each of said fashioning screws, said switch boxes being arranged to

control, during a resetting operation, the direction of racking.

7. A knitting machine as claimed in claim 6, wherein each of said switch boxes comprises a pair of contact switches, spring biased pivotally mounted contact arms for actuating said contact switches, a rockable cam plate for effecting movement of said contact arms, and a bifurcated switch arm fixed to said cam plate, said switch arm being arranged so that it is rocked by a projection attached to its associated nut housing. 5
